United States Patent

Des. 234,285
Patented Feb. 11, 1975

234,285

COFFEEMAKER

Chester H. Wickenberg, 164 Division St.,
Elgin, Ill. 60120

Filed July 30, 1973, Ser. No. 384,059

Term of patent 14 years

Int. Cl. D7—02

U.S. Cl. D7—85

Fig. 1.

Fig. 2.

Fig. 3.

FIG. 1 is a perspective view of a coffeemaker, showing my new design;

FIG. 2 is a side elevational view thereof, the opposite side being substantially the same;

FIG. 3 is a top plan view thereof.

I claim:

The ornamental design for a coffeemaker, as shown and described.
